UNITED STATES PATENT OFFICE

FRANK F. LANDIS, OF WAYNESBORO, PENNSYLVANIA.

VALVE.

1,071,759.

Specification of Letters Patent.

Patented Sept. 2, 1913.

Application filed September 5, 1906. Serial No. 333,320.

To all whom it may concern:

Be it known that I, FRANK F. LANDIS, a citizen of the United States, residing at Waynesboro, in the county of Franklin and State of Pennsylvania, have invented certain new and useful Improvements in Valves, of which the following is a specification.

In the use of electrically operated program clocks, it is desired at times to sound a signal at stated intervals, such signal being in some cases a steam or compressed air whistle. To provide a valve which may be controlled and operated by an electric current of moderate power, such as is used in a program clock apparatus, and thus provide for the operation of such a signal without interfering with the operation of the apparatus or requiring additional current or power, is the object of my present invention, and it consists in the particular construction and arrangement of parts hereinafter described and claimed, whereby these objects are attained, all as will be hereinafter more fully described and claimed.

Referring to the accompanying drawings which are made a part hereof and on which similar reference characters indicate similar parts, Figure 1 is a side elevation of a valve casing and operating mechanism embodying my said invention, Fig. 2 a cross section through the same on the dotted line 2—2 in Fig. 1, and Fig. 3 a horizontal section on the dotted line 3—3 in Fig. 2.

In said drawings the portions marked A represent the main body or casing of the valve, B a hood inclosing the valve mechanism, C the valve proper, D an auxiliary valve, and E a housing for supporting the electric valve actuating mechanism. The valve body or casing A is of suitable form for the purpose, having fittings at each end A' and A² for connection with a line of pipe. The entrance through the end A' leads into the chamber inclosed by the hood B. The valve seat comprises a bushing A³ mounted in a suitable screw-threaded seat in said body A between the inlet end A' and the outlet end A². The top of said bushing is formed with an annular face a dressed true to serve as a seat for the valve. Under the lower end of bushing A³ is mounted a soft metal packing ring a' to insure a tight joint. A central vertical standard A⁴ is formed integral with said bushing A³ being supported by radial arms a² projecting at intervals

from the interior of said bushing and joined to the said standard. Said arms are formed with passage-ways leading through them from the outside of said bushing to the lower end of a central passage a³ leading from near the lower end of said standard up and through its top. The outer ends of the passage-ways in the arms a² communicate with an opening a⁴ surrounding the lower end of bushing A³, as will be presently described.

The hood B is mounted upon the top of the valve body A in a suitably formed seat, being secured thereon by bolts b and adapted to inclose the valve mechanism and form a chamber to receive the fluid coming through the inlet end A'.

The valve C is formed to seat upon the valve-seat a upon the upper edge of bushing A³ and is formed with a central perforation which fits over the standard A⁴, on which said valve is thus adapted to slide vertically. On its top it is formed with a cylindrical portion C' exteriorly screw-threaded and having a cap C² mounted thereon to completely cover and inclose the top of said cylindrical portion. A piston-ring A⁵ is rigidly mounted upon the top of standard A⁴ and just fits within said cylindrical portion C'.

The auxiliary valve D is a small valve mounted upon a valve seat at one side of the main valve C in a bushing D', which is mounted in an aperture leading to the opening a⁴ surrounding the lower end of bushing A³. Said valve D is supported upon a stem d extending into a perforation in the upper end of a sliding rod d' which is mounted in a bushing D² extending through a perforation in valve body A. The lower end of said sliding rod d' is formed with a tapered perforation and is supported on the upper end of a stem d².

The housing E is a casting of substantially the form shown in Figs. 1 and 2 and is secured on the underside of the valve body A by bolts e. It is of a form adapted to support a pair of electro magnets E'. The cores E² of said magnets are connected at the ends opposite the armature by a yoke E³, which is formed with perforations fitting over said cores to which it is secured by screws e'. The ends of said yoke are secured to the sides of the yoke E by screws e². An armature E⁴ composed of a series of metal strips secured together by screws e³

is mounted upon a rock shaft E^5 adjacent to the opposite end of said magnets. The lower ends of said screws e^3 project into screw-threaded perforations in a bar e^4 connected by short arms e^5 with said rock shaft E^5 . Said rock shaft E^5 is mounted upon pivot screws e^6 which extend through the sides of the yoke E into suitable perforations in its opposite ends. The heads of the screws e^3 5 impinge against the top of a transverse bar e^7 on the lower end of an arm E^6 , which extends upwardly from the top edge of said armature and is pivoted at its upper end to the upper end of a short link E^7 , the lower 10 end of which is pivoted to one end of a lever E^8 , which is mounted upon a pivot e^8 in a suitable supporting bracket E^9 mounted on the body A . The two pivots connecting the opposite ends of link E^7 to arm E^6 and lever 15 E^8 are normally in line with the axis of the rock-shaft E^5 so that in operation the lever E^8 may be started in its movement toward the magnets with the least amount of power, the resistance offered at the start being practically nothing but increasing as the armature approaches the magnets and the power thus increases. A counter-balance weight e^9 20 is mounted on the opposite end of said lever E^8 . A circuit closer E^{10} , which may consist of an ordinary push button, or any device 25 to be operated by hand, but preferably a simple device to be operated by the program clock mechanism, is connected in the circuit with the magnets E' by wires e^{10} and e^{11} , one 30 of which is connected with a battery E^{11} of any suitable form. A cord or wire E^{12} is connected with the lever E^8 and runs over a sheave e^{12} to a place convenient to be seized by a handle e^{13} thereof, by which means 35 said lever E^8 may be operated independent of the clock or electrical mechanism when desired.

The operation of my said invention is as follows: The steam, compressed air or other fluid employed comes through the inlet end 40 A' of the valve body and into the chamber inclosed by the hood B . The pressure operates to keep valves C and D upon their seats and prevent further progress of said fluid. Under such pressure great power 45 would be required to lift valve C from its seat because of its size. For this reason the small auxiliary valve D is provided to aid in starting said movement, as follows: 50 When the circuit connecting the magnets E' with the battery E^{11} is closed by the circuit closer E^{10} , operated by hand or any mechanism, such as a program clock, said magnets are energized and the armature E^4 drawn 55 against the cores of said magnets, bringing the lever E^6 to the position shown by dotted lines in Fig. 2, which operates through the link E^7 to raise the end of lever E^8 to which the stem d^3 is pivoted, and through the 60 sliding rod d' and stem d raise the valve D 65

from its seat. Its upward movement is limited by an overhanging shoulder a^5 in the casing A just above the top of said valve D . Immediately upon said valve D being lifted from its seat the fluid under pressure 70 in the hood B rushes down through the opening in bushing D' into the channel a^4 surrounding the lower end of bushing A^3 , through the passage-ways in the arms a^2 and the passage a^3 in the upright A^4 , into the 75 space between the piston A^5 and the cap C^2 secured on the top of the cylindrical portion C' of the valve C . The area of the piston A^5 and interior of said cap C^2 being larger than the area of the valve C proper, 80 the pressure operates to raise said valve from its seat and permit the fluid under pressure to rush freely through the opening in the bushing A^3 and out through the outlet A^2 in the other end of the valve body 85 to the whistle or to operate, in any manner, to sound any character of alarm desired. The circuit closer E^{10} being released and the circuit broken, by hand or the operating mechanism provided, the weight of the 90 armature and of the valve D and parts which support it upon the lever B^6 will operate to cause said armature to fall back in the position shown in whole lines and the valve D to drop upon its seat on the top 95 of bushing D' which cuts off the flow of fluid through the passages a^4 , to under the cap C^2 and relieves the pressure in the cylinder C' beneath said cap, permitting the pressure of the fluid above the valve to gradually 100 seat it upon its seat a on the top of bushing A^3 , the seating being cushioned and made gradual because of the gradual leaking out of sufficient fluid under said cap C^2 to permit of the operation. The weight e^9 upon 105 the end of lever E^8 is of sufficient gravity to counter-balance the weight of the valve D and connecting parts so that the magnetic force is only required to lift the valve against the pressure of the fluid in the 110 chamber inclosed by the hood B .

In order to secure the greatest lifting power with the least magnetic force, I have arranged the connection between levers E^6 and E^8 so that the leverage is greatest when 115 the magnetic force is weakest as before mentioned. In Fig. 2, it will be noticed that when the parts are in the position indicated by whole lines the pivots connecting the link E^7 with the levers E^6 and E^8 are in line with 120 the axis of the rock shaft E^5 . Thus, when the magnets are first energized and the armature is the farthest away, but little resistance is offered to the starting of said armature toward said magnets in response 125 to the magnetic force. The upper end of lever E^6 moves toward the magnets and operates to enlarge the angle between the lever E^8 and the link E^7 , requiring greater power as the angle increases which is supplied 130

through the increased power secured by the narrowing of the field between the armature and the poles of the magnets. By this arrangement a comparatively weak battery or current is sufficient to energize the magnets with the magnetic power required to operate the several parts and lift the valve D.

Having thus fully described my said invention, what I claim as new and desire to secure by Letters Patent, is:—

1. In a valve structure, the combination of the valve body formed with inlet and outlet ports, a valve seat formed on a suitable bushing secured between said inlet and outlet ports, a main valve mounted on said valve seat, being held in position by a central standard supported by radial arms from said bushing, said arms and standard being formed with passage ways or ports communicating with a port surrounding said bushing, a small valve for closing a port or passage leading from the chamber surrounding said main valve into said ports, and means for raising said auxiliary valve at desired intervals, substantially as set forth.

2. In a valve structure, the combination of the valve body, comprising inlet and outlet ports separated by a main valve contained in a chamber communicating with the inlet port, an auxiliary port leading from said chamber to beneath a part of the main valve structure of larger area than the valve seat, an auxiliary valve for controlling said port, and means for operating said auxiliary valve comprising a lever connected therewith and pivoted to an arm of an armature of an electromagnet, said electromagnet mounted in an electric circuit adapted to be opened and closed, and means

for opening and closing said circuit, substantially as set forth.

3. In a valve structure, the combination of the valve body, the main valve, the auxiliary valve for controlling a port leading to beneath a part of the main valve, means for operating said auxiliary valve comprising a lever connected by a link with an arm mounted on a swinging armature of an electromagnet, the pivots connecting the opposite ends of said link with said lever and arm being normally substantially in line with the axis of the pivot or shaft on which said armature is mounted, said electromagnet mounted in an electric circuit, and means for opening and closing said circuit, substantially as set forth.

4. In a valve, the combination, of a body provided with an inlet and an outlet, a main valve between them, an auxiliary valve controlling a port leading from one side of said main valve to the other, means for operating said auxiliary valve comprising an electromagnet, the armature thereof mounted on a rock-shaft and having an arm connected to a lever for lifting said auxiliary valve, the connection consisting of a link pivoted at one end to said arm and at the other end to said lever, the pivots being arranged so that the angle between the link and arm will increase as the armature moves toward the magnets, substantially as set forth.

In witness whereof, I have hereunto set my hand and seal at Washington, D. C., this 28th day of August, A. D. nineteen hundred and six.
